SAFETY APPLIANCE FOR TRAINS.

1,134,999.

Specification of Letters Patent. Patented Apr. 13, 1915.

Application filed June 14, 1913. Serial No. 773,646.

To all whom it may concern:

Be it known that I, JOHN J. DEGENHARDT, citizen of the United States, residing at Elkville, in the county of Jackson and State of Illinois, have invented certain new and useful Improvements in Safety Appliances for Trains, of which the following is a specification.

My invention relates to new and useful improvements in safety appliances for railways and more particularly to attachments for trains adapted to be actuated by danger signals positioned along the track upon the trains running past a signal set in danger position to vent the air line and apply the brakes of the train, the principal object of my invention being to provide an appliance of the above described character which may be operated by means of the arms of the usual semaphores now employed in railway signaling.

A further object of my invention is to provide in connection with a valve for venting the air line, a simple and effective structure for operating the valve which will be positively actuated by the semaphore arm when the latter is in active position and which will be held against movement until so actuated.

With these and other objects in view, my invention will be more fully described, illustrated in the accompanying drawings, and then specifically pointed out in the claims which are attached to and form a part of this application.

In the drawings: Figure 1 is an elevational view of a conventional form of locomotive showing my appliance in position thereon, a portion of the cab being broken away to more clearly show certain details; Fig. 2 is a transverse sectional view on the line 2—2 of Fig. 1, showing the manner of mounting the actuating mechanism for the valve; Fig. 3 is a longitudinal sectional view of the valve and valve actuating mechanism; Fig. 4 is a similar view, the section being taken at right angles to that shown in Fig. 3; Fig. 5 is a detail sectional view of the valve casing and valve.

Corresponding and like parts are referred to in the following description and indicated in all the views of the drawings by the same reference characters.

As my improved safety device is intended

merely to vent the air line and apply the air brakes of a train when actuated by a semaphore arm or other suitable device located adjacent the track, it will be apparent that the same may be mounted upon any portion of the train. Inasmuch however, as the locomotive is one unit common to all trains I prefer to mount the appliance thereon.

In Fig. 1, a conventional form of locomotive is indicated at 10 and this locomotive is provided with an air line pipe 11 which extends throughout the entire length of the locomotive being provided at one end with a coupling 12 by which it may be connected with the air line of the train and at its opposite end with a second coupling 13 which may be employed when the locomotive is to be attached to the rear end of a train. In installing my safety appliance I provide a branch pipe 14 which leads from the pipe 11 to a valve 15, the construction of which will be later explained. The opening of this valve 15 will vent the air line and apply the brakes and as a means for opening this valve I provide a mechanism indicated as a whole by the numeral 16.

Referring more specifically to Figs. 2 to 5 inclusive, it will be seen that the valve operating mechanism 16 includes a shaft 17, which extends transversely through the roof or upper portion of the locomotive cab, being journaled in suitable bearings 18 carried by the cab and held against longitudinal movement through the bearings by collars 19 secured upon the shaft by set screws 20. The ends of the shaft are squared or otherwise formed with angular faces and are preferably tapered as shown at 21 to receive actuating arms 22 having squared openings in their ends to seat the squared portion of the shaft. The extreme ends of the shaft are threaded to receive nuts 23 by which the actuating arms are locked in place. The shaft within the cab carries a collar 24 secured by a set screw 25 and having an integrally formed indicating finger 26 which extends downwardly when the arm 22 extends upwardly.

Secured against rotation upon the intermediate portion of the shaft 17 by a key 27, is a disk 28, this disk being eccentrically mounted upon the shaft. Surrounding this disk are a pair of semicircular castings 29

and 30 forming an eccentric strap for the disk being secured together by bolts 31 passed through perforated ears 32 formed upon the adjacent ends of said casting. The 5 casting 29 is formed with a recess 33 in its inner face and a bore 34 leading from this recess communicates with an enlarged socket 35 formed in a radial extension 36 of the casting. A brake 37 is seated in the recess 10 33 and has a centering stud 38 which passes through the bore into the socket 35.

A helical spring 39 is positioned in the socket 35 and bears against the end of the centering stud to force the brake into frictional engagement with the peripheral edge of the disk 28, this helical spring being held against lateral movement by projections 40 formed upon the free end of the centering stud and upon the inner wall of the socket 20 forming portion 36 of the eccentric strap. Said portion 36 is provided at one side with a series of longitudinally extending spaced 25 grooves or corrugations 41 adapted to receive the laterally directed terminal 42 of a resilient locking arm 43 which is secured at its opposite end by a screw 44 to the central portion of the disk 28. It will therefore be seen that both the brake and the resilient locking arm 43 serve to hold the eccentric 30 strap in a predetermined position with respect to the eccentric disk 28, this position being that which the disk occupies when the arms 22 of the shaft 17 extend vertically upward or when the indicator arm 26 extends downward.

The free end of the extended portion 36 of the eccentric strap member 30 is provided with an internally threaded bore 45 to receive the reduced threaded end of a rod 46, 40 the free end of which is hingedly connected as at 47 to a second rod 48, the free end of which is in turn provided with an internally threaded bore 49 adapted to receive the reduced threaded end 50 of a reciprocating 45 valve stem 51 of the valve 15. This valve stem is journaled in a bearing sleeve 52 carried by the front wall 53 of the locomotive cab.

The valve 15 includes a casing 54 provided at one side with an inlet port 55 to which the free end of the pipe 14 leads and at its other side with an exhaust port 56. The valve stem 51 extends through a stuffing box 57 formed in the rear wall of the valve 55 casing and carries a slide valve 58. This slide valve includes a body forming block 59 through which the inner end of the valve stem 51 is passed, said end being threaded to receive jam nuts 60 by means of which 60 the block is locked against longitudinal movement. A set screw 61 serves to secure the block 59 against rotation upon the valve stem. That wall of the valve casing through which the exhaust or inlet port 56 is formed 65 is plane surfaced and the block 59 carries a

plane surfaced plate 62 which is slidable on said casing wall face to either cover the valve opening therethrough or to expose the same according to the position of the valve. This plate is held in frictional engagement 70 with the valve seat and against movement independently of the block 59 by pins 63 which are slidable in bores 64 formed in the block and which seat by their ends in sockets 65 formed in the plate, these pins being held 75 in position by helical springs 66 which bear between the outer ends of the pins and screws 67 threaded into the outer ends of the bores 64. The valve stem is so proportioned that when the eccentric and eccentric strap 80 occupy the position shown in Figs. 3 and 4 of the drawings—that is, when the actuating arms of the appliance are in upright position, as shown in Fig. 1, the valve will extend over the outlet port 56 of the valve casing and prevent the escape of air from the air line.

The ends of the shaft 17 extend a sufficient distance from either side of the locomotive to bring the actuating arms 22 in line with semaphore arms 68 swingingly mounted upon signal posts 69, when said arms are lowered to extend at right angles to the post, that is, when said arms are set in danger position, as shown in Fig. 2, from which figure the operation of my safety appliance will be readily understood, slight description being therefore necessary.

The semaphores will be set in danger or safety position in the usual manner and it will be apparent that if the engineer fails to see the signal when set in danger position and attempts to run the train past the same, the engagement of the actuating arms 22 against the semaphore arms will cause a partial rotation of the shaft 17 and act through the eccentric disk 28 and eccentric strap to reciprocate the valve stem 51 and open the valve to vent the air line of the train and apply the air brakes.

It will of course be understood that I do not wish to limit myself to the details of construction set forth as various minor changes, within the scope of the appended claims, may be made at any time, if desired, without in the slightest degree departing from the spirit of my invention.

Having thus described the invention, what is claimed as new is:

1. In a semaphore arm actuated safety appliance for locomotives, the combination with an air brake line, of a vent valve in said line, a rotatable shaft, an arm carried by the shaft and extending in the path of a lowered semaphore arm, an eccentric disk 125 mounted on the shaft, a strap for the disk, an operative connection between the strap and valve stem, and a brake carried by the strap and engaging the disk.

2. In safety appliances for locomotives, a 130

shaft extending transversely of the locomotive and provided at its free ends with upwardly directed arms adapted for engagement by obstacles located adjacent the track, 5 a disk eccentrically keyed upon the shaft, a strap surrounding the disk, a spring pressed brake carried by the strap and frictionally engaging the disk, a valve adapted for connection with the air brake line of the locomotive and having a reciprocating valve stem, and a hinged connection between the strap and valve stem.

3. In safety appliances for locomotives, a shaft extending transversely of the locomotive and provided at its free ends with upwardly directed arms adapted for engagement by obstacles located adjacent the track, a disk eccentrically keyed upon the shaft, a strap surrounding the disk, a spring 15 pressed brake carried by the strap and frictionally engaging the disk, a valve adapted for connection with the air brake line of the locomotive and having a reciprocating valve stem, a hinged connection between the strap and valve stem, and means in addition to the brake for normally holding the eccentric disk and strap against independent movement.

4. In safety appliances for locomotives, a shaft extending transversely of the locomotive and provided at its free ends with upwardly directed arms adapted for engagement by obstacles located adjacent the track,

a disk eccentrically keyed upon the shaft, a strap surrounding the disk, a spring pressed 35 brake carried by the strap and frictionally engaging the disk, a valve adapted for connection with the air brake line of the locomotive and having a reciprocating valve stem, a hinged connection between the strap 40 and valve stem, and means in addition to the brake for normally holding the eccentric disk and strap against independent movement, said means including a resilient arm secured to the eccentric disk and having a 45 laterally directed terminal seating in a groove formed in the strap.

5. In safety appliances for locomotives, a rotatable shaft having radial arms adapted for engagement by obstacles located adjacent the track, a disk eccentrically keyed upon the shaft, a strap surrounding the disk, said strap having a groove, a resilient member secured at one end centrally of the disk and provided at its opposite end with a laterally directed terminal seating in the groove of the strap, a valve adapted for connection with the air brake line of the locomotive, and operative connection between the strap 55 and valve.

In testimony whereof I affix my signature in presence of two witnesses.

JOHN J. DEGENHARDT. [L.S.]
